DESIGN FOR A FRONT PLATE FOR THE HEAD OF A COIN CONTROLLED MACHINE CASING

Thomas W. B. Watling, Chicago, Ill., assignor
to Watling Manufacturing Company, Chicago,
Ill., a corporation of Illinois

Application September 21, 1934, Serial No. 53,347

Term of patent 7 years

To all whom it may concern:

Be it known that I, Thomas W. B. Watling, a citizen of the United States, residing in Chicago, county of Cook, and State of Illinois, have invented a new, original, and ornamental Design for a Front Plate for the Head of a Coin Controlled Machine Casing, of which the following is a specification, reference being had to the accompanying drawing forming a part hereof.

In the drawing:

Fig. 1 is a front elevation of the front plate for the head of a coin controlled machine casing embodying my new design.

Fig. 2 is a side elevation of the same.

I claim:

The ornamental design for a front plate for the head of a coin controlled machine casing substantially as shown.

THOMAS W. B. WATLING.
